UNITED STATES PATENT OFFICE.

JULIUS J. TREFZ, OF OWENSBORO, KENTUCKY, ASSIGNOR TO THE ANGLO-AMERICAN MILL CO., OF OWENSBORO, KENTUCKY, A CORPORATION OF KENTUCKY.

SCALPER FOR SELF-CONTAINED FLOUR-MILLS.

1,229,169.

Specification of Letters Patent. Patented June 5, 1917.

Application filed July 3, 1916. Serial No. 107,387.

To all whom it may concern:

Be it known that I, JULIUS J. TREFZ, a citizen of the United States, residing at Owensboro, in the county of Daviess and State of Kentucky, have invented new and useful Improvements in Scalpers for Self-Contained Flour-Mills, of which the following is a specification.

The present invention relates to flour mills of the self-contained type, and which are characterized by close assembling of milling and bolting instrumentalities, so that "short system" milling, which is now largely in favor, may be effected.

It has particularly to do with the "scalping" of the stock, which operation is the sieving out of the finer stock from the coarser material preliminary to the finer stock passing to the bolting reels, and has for its object to provide a combination of breaking, scalping, and bolting elements in which the scalping operation will be quickly and thoroughly performed in line with the general principles of "short milling", and which will relieve the bolting reels from excessive wear, due to the silks being subjected to the action of unscalped stock.

In the present disclosure I have shown two embodiments of my invention, but it will be understood that it may be mechanically varied from this illustrative disclosure, and that I do not restrict myself to the precise expedients herein set forth.

In the drawings which accompany and form a part of this application.

Figure 1 is a view in side elevation of so much of a self-contained mill as is essential to an understanding of my invention.

Fig. 2 is an end view looking from the left of Fig. 1.

Fig. 3 is a view partly in section showing the scalper feed hopper.

Fig. 4 is a view in side elevation of the hopper shown in Fig. 3.

Fig. 5 is a side elevation partly in section of a part of the mill showing a different form of scalper.

Fig. 6 is an end view of the mechanism shown in Fig. 4, looking from the right on substantially the line 6—6, Fig. 5.

In mills of the self-contained type, it is common to have two distinct sections mounted closely adjacent in the casing, one section being the "break" section, and the other the "dressing" or "bolting" section, the break

section receiving the grain, breaking it, and then passing it to the dressing or bolting section for separation, suitable conveying means being provided, and customarily the stock is subjected to several sets of break 60 rolls and reduction rolls, passing alternately from the break section to the bolting section, until complete reduction of the grain and separation of the flour, middlings and bran has been effected.

Referring to the drawings by numbers, like numbers indicating like parts in the several views, 10 indicates the main frame of the break section, in which frame is mounted, in suitable bearings, the first set 70 of break rolls 11, below which may be a second set of break rolls 12, and additionally the break section is provided with what are known as reduction rolls (not shown) for final treatment of the stock. Adjacent the 75 frame 10 of the break section is the main frame 13 of the bolting or dressing section of the mill, and suitably mounted in this main frame are the bolting reels, one reel 14 being shown in the present instance, this being 80 the first break bolting or dressing reel.

When the stock comes from the first break rolls 11 it contains, of course, all of the elements of wheat, including the coarser particles, and various means have been proposed to separate out or scalp these coarser particles so that the reel would not be subjected to the action of the heavier and coarser material, which very quickly wears out the silks. It has been proposed to carry 90 the product of the break rolls directly to the bolting reel, pass them therethrough while subjecting them to a bolting action, scalp out the coarser particles at the end of the reel farthest from the break rolls, and 95 return the tailings to the second break rolls for further treatment, but this method is open to the objection just stated, that the bolting reel is subjected throughout this entire length to the action of the coarse bran. 100 It has been proposed further to provide a scalping sieve directly beneath the break rolls in the roll section, and while this system is far superior to the other method it is open to some objections which the present 105 scalping instrumentalities are designed to overcome.

I have utilized the fact that mills of this type are divided into distinct units, namely, the breaking unit and the dressing unit, to 110

place the scalper intermediate the break section and the dressing section, where it may act preliminarily on the stock coming from the break rolls, and so deliver scalped stock 5 to the reel, returning the tailings to the second break rolls, and by so doing have not increased to any material extent the distance from the break rolls to conveyers, and have materially decreased the conveyer flights 10 necessary to return the tailings, as compared with those systems in which the stock is carried through the bolting reels; scalped at the far end, and the tailings returned.

I accomplish this by placing between the 15 frames 10 and 13, as shown in Fig. 1, a scalping screen, which, in the form disclosed in Figs. 1 and 2, is a shaking screen 15 having a suitable frame with grits gauze thereon, this screen being mounted in the 20 inclined position shown in Fig. 2, provided with suitable supports, and having also a vibrating mechanism to impart shaking movements to it, this vibrating mechanism being of any desired type, and so not described in detail.

Just above the screen 15 is the feed hopper 16, which feed hopper extends laterally across the screen, the hopper being of a length equal to the width of the screen surface, so that equal distribution of the material over the screen will be secured. Said hopper 16 has the inclined bottom 17, as shown in Fig. 3 and a hinged door or gate 18, which is normally held closed by the 30 weighted lever 19 pivoted to a fixed part of the hopper, and provided with an adjustable weight so as to vary the pressure necessary to open the gate. With this construction stock delivered to the hopper will, 35 when sufficient quantity has accumulated, force the gate open and maintain an even feed of the stock from the hopper to the screen 15.

The said hopper receives the end of a conveyer 20, which conveyer projects through a suitable trough 21 lying beneath the first break rolls 11, and as the stock comes from said break rolls 11 and is delivered to the trough 21 the conveyer 20 therein will carry 50 it forward and deliver it to the hopper 16, which, through its automatically operating gate, will spread it in an even layer across the screen 15, down the inclined surface of which it will pass, screening out the 55 throughs, which will be carried by the conveyer 22 to the reel 14 to be subjected to the dressing operation.

The coarser material will fall from the lower end of the screen 15 to the trough 23 60 from which they are conveyed by conveyer 24 back to the roll section of the mill, and delivered to a fall board 25, down which they pass to the second break rolls 26 for further reduction.

65 In the form of the invention shown in

Figs. 5 and 6 the scalper is shown in the form of a cylinder 27, this scalper being located between the frames of the break section and the bolting section of the mill. The scalper 27 will be similar in construction to an ordinary bolting or dressing reel having suitable heads or spiders 28 and side bars to support the perforate material, preferably grits gauze, 30. The scalper 27 will preferably be carried by the conveyer shaft 35 which brings the stock from the first break rolls, this conveyer shaft being extended and upon a bearing in the main frame of the reel section of the mill, as shown in Fig. 5. The scalper reel will be 80 hooded or inclosed by the case 32, which hood has a depending portion to form a receiving trough 33 for the throughs, in which trough is a conveyer 34 mounted on the extended end of the shaft 35 of the reel 36, so 85 that the material bolted by the scalper will, by the conveyer 34, be carried forward to the bolting reel 36. At the delivery end of the scalper reel 27 is an overtails spout 37 to which, through the delivery orifice 38 of 90 the scalper reel, the scalped stock will be delivered. The said spout 37 delivers to an overtails conveyer 39, which overtails conveyer returns the tailings to the break section of the mill, directing them to a fall 95 board 40, down which they pass to the second break rolls 12.

With the construction above described a very efficient scalping of the stock may be secured, and at the proper point, for eliminating so far as possible that part of the stock it is undesirable should pass to the dressers, namely, at a point immediately after the first break rolls have acted on the grain. It is accomplished furthermore 100 without increasing to any material degree the size of the mill, and without the necessity of any material alteration in the instrumentalities now used for "short milling", and the handling of both the stock, 110 the material to be bolted in the reel section, and the tailings, is reduced to short flights, the whole arrangement being such that deterioration of the reel silks, by reason of the introduction to that section of coarse 115 and heavy stock, is entirely done away with.

It will be understood that while I have shown this scalping instrumentality only in connection with the first break rolls, where its use is desirable in the type of mill 120 referred to, I do not limit myself to this specific location of it, as it is obvious that the scalper may be used at any point, and in any relation to the breaking and bolting instrumentalities where it is desirable to 125 scalp out of the product coming from the roll section, and prior to passing to the bolting section, any part of the stock.

I claim:

1. In a self-contained flour mill having 130

- the usual break section and bolting section, and in combination, break rolls in said break section, a bolting reel in said bolting section, means directly between said sections and intermediate said rolls and reel to scalp the stock coming from the break rolls, and means to convey the stock from said break rolls to said scalping means. 2. In a self-contained flour mill and in combination, a plurality of sets of break rolls, a bolting reel, means directly between the break and bolting sections of the mill and intermediate said rolls and reel to scalp the stock coming from one set of break rolls, means to convey the stock from said break rolls to said scalper, means to convey the throughs to said bolting reel, and means to return the tailings to a second set of said break rolls. 3. In a self-contained flour mill and in combination, break rolls, a bolting reel, means directly between the break and bolting sections of the mill to scalp the stock coming from the break rolls, means to distribute the stock to said scalper, means to convey the stock from said break rolls to said distributing means, and means to convey the throughs to said bolting reel. 4. In a self-contained flour mill and in combination, break rolls, a bolting reel, a scalping screen directly between the break and bolting sections of the mill, stock distributing means for said scalper, means to convey the stock from said break rolls to said distributing means, and means to convey the throughs to said bolting reel. 5. In a self-contained flour mill and in combination, a plurality of sets of break rolls, a bolting reel, an inclined scalping screen directly between the break and bolting sections of said mill, a distributing hopper having an automatic feed gate above said screen, means to convey the stock from one set of said break rolls to said hopper, means to convey the throughs to said bolting reel, and means to return the tailings to a second set of said break rolls. 6. In a self-contained flour mill and in combination, a plurality of sets of break rolls, a bolting reel, means directly between the break and bolting sections of said mill to scalp the stock coming from the break rolls, a conveyer beneath said break rolls delivering to said scalping means, a conveyer extending from said reel to said break rolls to convey the throughs to said bolting reel, and a conveyer to return the tailings to a second set of said break rolls. 7. In a self-contained flour mill having
- the usual break section and bolting section and in combination, break rolls in said break section, a bolting reel in said bolting section, means directly between said sections and intermediate said rolls and reel to scalp the stock coming from the break rolls, means to convey the stock from said break rolls to said scalper, and means to convey the throughs to said bolting reel. 8. In a self-contained flour mill having the usual break section and bolting section and in combination, break rolls, a bolting reel, an inclined scalping screen positioned between said sections intermediate said rolls and reel, a distributing hopper above said screen, means to convey the stock from said break rolls to said hopper, and means to convey the throughs to said bolting reel. 9. In a self-contained flour mill having the usual break section and bolting section and in combination, a plurality of sets of break rolls in said break section, a bolting reel in said bolting section, an inclined scalping screen located in the space between said break and bolting sections intermediate said rolls and reel, a distributing hopper above said screen, means to convey the stock from said break rolls to said hopper, means to convey the throughs to said bolting reel and means to return the tailings to a second set of break rolls. 10. In a self-contained flour mill having the usual break section and bolting section and in combination, break rolls in said break section, a bolting reel in said bolting section, a screen located in the space between said sections intermediate said rolls and reel to scalp the stock coming from the break rolls, a distributing hopper extending laterally across the screen and being substantially of a length equal to the width of the screen surface, an automatic feed gate on said hopper, a trough beneath said break rolls leading to said hopper, a screw conveyer in said trough and hopper for feeding the stock from the break rolls to said screen, a conveyer beneath said break rolls extending to said reel to convey the throughs to said bolting reel, and a conveyer to return the tailings to said first set of break rolls. In testimony whereof I have hereunto set my hand in presence of two subscribing witnesses.

JULIUS J. TREFZ.
